[57] **CLAIM**

The ornamental design for a foldable wheelchair, substantially as shown and described.

DESCRIPTION

FIG. 1 is a right side elevational view of a foldable wheelchair showing my new design;

FIG. 2 is a left side perspective view of my new design in a folded condition with the armrests and footrests removed; and

FIG. 3 is a front perspective view of my new design. The rear of the back rest of the foldable wheel chair is understood to be flat and unornamented.

FIG.1

FIG.2

FIG.3
